UNITED STATES PATENT OFFICE.

EMMET HORTON, OF DUNDEE, NEW YORK.

COMBINED HAMMER AND NAIL-FEEDING DEVICE.

SPECIFICATION forming part of Letters Patent No. 331,060, dated November 24, 1885.

Application filed March 3, 1885. Serial No. 157,679. (No model.)

To all whom it may concern:

Be it known that I, EMMET HORTON, of Dundee, in the county of Yates and State of New York, have invented certain new and useful Improvements in Nailing-Hammers, of which the following is a full, clear, and exact description.

The subject of this invention is a hand-hammer for nailing purposes, in which, as in another portable hand nailing-hammer invented by me and claimed in a prior application, filed March 3, 1884, Serial No. 122,772, there is combined a receptacle for carrying nails, a hammer-head below the same, a feeding incline or duct for the nails from the receptacle, a device for clamping or holding each separately-delivered nail before setting and driving it, and a handle at right angles, or thereabout, to the hammer-head, and whereby by the swinging motion of the hammer is made to automatically feed the nails, one by one, to the clamping device, and on release of the clamp which holds the nail in position for being set and driven the nail is or may be driven home by the head of the hammer when suitably swung or raised and brought down for the purpose on the nail-head.

This invention consists in an improved or novel construction of a hammer of this description, including various details and combinations of details, substantially as herein-after described, and whereby a very perfect result or action is obtained.

The invention is not restricted to any particular size or description of nail, nor yet to any special class of work; but it will be found of great convenience to carpenters, masons, and others for shingling, lathing, nailing boxes, and other purposes.

Reference is to be had to the accompanying drawings, forming part of this specification, in which similar letters of reference indicate corresponding parts in all the figures.

Figure 1 represents a partly-sectional longitudinal and side or vertical view of a hand or portable nailing-hammer embodying my invention. Fig. 2 is an inverted or under longitudinal view of the same; Fig. 3, a section on the line xx in Fig. 1; Fig. 4, a section on the line yy in Fig. 1; and Fig. 5 is a section on the line zz in Fig. 1.

A indicates the hammer-handle, attached to and projecting in front of the inner end of which is a vertically-slotted metal main frame, B, that is made to form or has secured to its lower end, in front, the hammer-head C, which is arranged to occupy a position at right angles, or thereabout, to the handle.

D is the box or receptacle for holding the nails, mounted on and connected with the frame B in any suitable manner, and mainly of curved marginal configuration on its interior, but sloping upward in a backward direction at its bottom, and that has connected with and beneath it the nail-delivering duct or guide E, for the nails, of corresponding inclination, or thereabout, to the bottom of the nail-receptacle.

The side of the nail box or receptacle D is provided with a lid or door, b, of any suitable description, for introducing the charge or load of nails that are thrown promiscuously into the box, or rather into the main central portion of it, which is contained within a partition, F, connecting the sides of the box at its top, back, and front, and bottom in part, but stopping short at its upper and lower forward ends, and being so arranged within the box, to the marginal configuration of which it conforms, or nearly so, as to leave between it and the marginal interior of the box or such portion thereof as it faces a curved or partially-curved way or channel, G, for the nails in their passage from the box. Said partition or inner wall of the way, G, it is preferred to make yielding and adjustable—as by a screw and slot, e, at its mouth end d—to adapt said way for the reception of different-sized nails. The opposite and lower front end of the channel G is open for discharge of the nails and return of any surplus quantity from said channel back to the box. By throwing or jerking the hammer upward or otherwise suitably manipulating it a certain quantity of nails from the mass within the center of the box are tossed or thrown up into the channel G through its mouth end d, a divider, H, if desirable, extending from the mouth of the channel to the bottom of the box intermediately of the width of the latter, serving to separate the entering nails so as to give them free or better admission into the channel G and prevent them from

jamming at the mouth of said channel or way. The same or repeated similar jerking action of the hammer causes the nails admitted to the channel G to be carried or projected along and through it, subject to the controlling effect of an adjustable throttle-valve-like regulator, I, at or near the top of the channel when the hammer is down. This regulator, which may be of any suitable construction, serves to further separate the nails and to limit the number of them which shall pass down the back and under part of the channel at any one time. The bottom of the outer wall of the box has a longitudinal slot, e, in its rear portion of sufficient width to receive the passing nails, heads and all, within it, and in front of this slot is a raised curved stop, f. This curved stop f serves, in conjunction with the nail-delivering duct or guide E, that is vertically divided or slotted longitudinally, to direct and turn the head of each nail in succession and to permit of the nail-heads passing beneath it and out of the channel G onto the lower portion, g, of the upper surface of the guide, and so that the nails may be pendent by their heads beneath the bottom of the box as they slide down the inclined guide E, the slot h in which serves to receive the shanks of the nails down through it, and is extended the full length of the guide, or thereabout. Such raised curved stop f dispenses with an enlarged opening for the nail-heads in the inclined guide, and in case of small nails being worked insures a proper position for them. The guide E has one of its sides made loose and adjustable laterally toward or from its opposite side by means of screws i i and rubber or elastic packing blocks or pieces k k, to vary the width of the slot h to suit different-sized nails. When the suspended nails have passed down the inclined guide E, they are arrested at the foot of it by a cut-off lip or portion, l, of a cross-swinging combined cut-off and separating-hook, S, pivoted, as at m, and actuated by a sliding trigger, J, which is controlled by a spring, n. The cut-off lip l works across the lower end of the slot h in the guide E, while the hook-piece l' of the combined cut-off and separating-hook S works through a front cross-slot, o, below the upper surface of the guide E, to take the shank of each advance pendent nail in succession.

In the normal position of the device S and of the trigger J the latter is held forward by its spring n, and the device S locked or held so that its cut-off lip l closes the lower end of the slot h in the guide E by the frame B on the one side and an upright arm, r, of the sliding trigger on the other side or within a projecting nose part, s. On pulling the trigger J back, however, against the tension of its spring n, which is done by a finger of the hand holding the hammer, the arm r strikes and presses upon the device S, to turn or swing it on its pivot, so as to cause its cut-off lip l to uncover or expose the front open end of the slot h, and at the same time to project the

hook-piece l' through the lower front slot, o, till arrested by a suitable stop—as, for instance, by a projection, a', striking the frame B. This projecting of the hook-piece l' causes said piece to pass back of the shank of the advance nail b' below the front end of the slot h, and to pick said nail out from the other nails in rear of it, which the hook-piece l' then acts as a stop or cut off to, and to pass the advance nail down into the slotted portion o, from or out of which in front said nail, pendent by its head, drops into or in front of the clamp, which holds the nail while being set. The hook or hook-piece l' is or may be made adjustable in or out, and be secured by a setscrew, l', to adapt it to work in more or less close proximity to the shoulders formed by the back of the slot o, to enable it to pick out or separate different-sized nails. On releasing hold of the trigger J its spring n throws it forward, and in so doing the arm r acts upon the inside of the nose part s, to return the device S to its normal position, and to bring its cut-off lip l in closing position with the lower end of the slot h as the hook-piece l' passes from under said slot for a repetition in due course of its separating action, as before. It thus will be seen that the cut-off lip l and hook-piece l' operate alternately to stop the delivery of the nails from the slot h of the guide, and that when the hook-piece l' acts as a cut-off it also operates as a picker-out of the advance nail. In this way only one nail can be taken at a time.

Other means than the spring-trigger here shown may be used for operating the combined cut-off and separating-hook S.

When the device S is operated to pick out and deliver a nail, as described, a clamp, K, which is a pendent one pivoted, as at c', to the one side of the frame B, is extended below, so as to come immediately in rear of the hammer-head C, or of a fixed grooved clamping-piece and guide d for the delivered nail, to permit of the nail falling to its place for setting it in the work. This clamp K is a tension one, it being controlled and closed upon the nail by a spring, e'. Said clamp may be opened or drawn back against the tension of its spring to receive the nail by operating it either directly or through its spring, which may be adjustable by a screw, f', by a projection, j, on the trigger J, as shown, so that on pulling back the trigger the clamp is opened or removed to receive the nail, and on releasing hold of the trigger it is thrown forward by its spring to clamp or hold the nail while being set. This lower tension applied to the clamp K is sufficient to hold the nail while setting it in the work by throwing or driving the hammer as it holds the nail; but by jerking the hammer upward again the clamp is released from the nail thus stuck into the wood—or, in other words, the spring-clamp slipped from off the stuck nail—when or after which the nail may be driven home by striking it on its head with the hammer-head.

Having thus described my invention, what I claim as new, and desire to secure by Letters Patent, is—

1. In a nailing-hammer provided with a handle in angular relation with its head, a raised nail box or receptacle, and an inclined guide or duct for conveying the nails from the lower portion of said receptacle to the forward portion of the hammer, the nail box or receptacle D, of curvilinear marginal configuration, provided on its interior with an outer mainly-curved way, G, open at its forward and lower ends for passage of the nails through it from the interior of the box, substantially as specified.
2. The divider H, in combination with the nail box or receptacle D of the hammer and the partition F, forming the inner wall of a curved outer way or passage, G, within the box, essentially as described.
3. The curved nail-box D of the hammer, having in its interior an outer curved way, G, for passage of the nails, provided with an adjustable regulator at or near its top for separating and restricting the passage of the nails through said way or channel, substantially as specified.
4. The curved way or nail-passage G of the box, made adjustable at its mouth end relatively to the front of the box, essentially as described.
5. The nail-holding box D of the hammer, having a slot, e, in its base, and provided with a raised stop, f, at foot of said slot, in combination with the slotted inclined nail guide or duct E, substantially as and for the purpose specified.
6. The slotted nail guide or duct E, having its one side adjustable relatively to the other,

in combination with the elastic blocks k and 40 screws i, essentially as described.

7. In a hand nailing-hammer in which the nails are passed from a raised box or receptacle by the working or using of the hammer, the combined nail cut-off and separating-hook 45 S, provided with a hook end or piece, l', and a cut-off lip, l, substantially as and for the purposes specified.

8. The combined nail cut-off and separating-hook S of the hammer, having its hook-piece l' made adjustable in or out, in combination with the inclined nail guide or duct E, having slots h and o, for operation in relation with each other essentially as specified.

9. The combination of the trigger J of the 55 hammer with the pivoted combined nail cut-off and separating-hook S and the inclined nail guide or duct E, substantially as described.

10. The pivoted pendent clamp K, controlled 60 by a spring, as described, in combination with the hammer-head C, essentially as specified.

11. The combination of the spring-actuated trigger J with the spring-actuated pendent clamp K and the hammer-head C, the adjacent faces of the hammer-head and clamp being correspondingly grooved to receive a nail, substantially as described.

12. The combination, with the handle and head of the hammer, of the spring-actuated 70 trigger J, the combined nail cut-off and separating-hook S, the inclined nail guide or duct E, and the spring-actuated clamp K, essentially as specified.
